UNITED STATES PATENT OFFICE.

WILLIAM H. DOSS, OF BENTON CITY, MISSOURI.

RAZOR-STROP.

SPECIFICATION forming part of Letters Patent No. 739,584, dated September 22, 1903.

Application filed October 20, 1902. Serial No. 128,031. (No model.)

To all whom it may concern:

Be it known that I, WILLIAM H. DOSS, a citizen of the United States, residing at Benton City, in the county of Audrain and State of Missouri, have invented a new and useful Razor-Strrop, of which the following is a specification.

This invention relates to razor-strops, and has for its object the production of a device of this character wherein the operative surfaces of the strop are interrupted or formed with an irregular surface, whereby the strop more closely conforms to the edge of the razor and the abrasiveness increased without any increase in the labor or the wear upon the razor edge; and to this end the invention consists in a strop formed of a single piece of flexible material having a plurality of closely-spaced transverse perforations or apertures in its body through which any grit or accumulation may be forced from the face of the strop by the operation of the razor during the process of stropping the same, and, if desired, the opposite sides of the strop may be constructed of different degrees of abrasiveness.

Other novel features of the invention will be disclosed in the annexed description and be specified in the claims following.

In the drawings illustrative of the invention, Figure 1 is a plan view of a razor-strop embodying the improvements. Fig. 2 is a transverse section, enlarged, of the same.

The improved strop will preferably be formed of a single piece of leather of the usual quality having different degrees of abrasiveness upon its opposite sides and of the usual shape and size, with a handle upon one end and a relatively large perforation in the other end, this perforation providing for the support of the strop upon a hook or other fastening while in use in the ordinary manner.

The body of the strop is indicated at 10, the handle portion at 11, and the supporting-perforation at 12, as shown.

45 The body of the strop will be provided with a plurality of closely-spaced perforations 13, passing entirely through the strop at right angles to its operative surfaces, as indicated in Fig. 2. By this simple means the opera-
50 tive surfaces of the strop are interrupted or formed with alternating smooth surfaces be-
tween the perforations, interrupted by the

perforations, so that the razor in being drawn back and forth over the strop is subjected to a greatly-increased abrasive action and every portion of the cutting edge engaged by a plurality of the interrupted surfaces, thereby not only greatly increasing the abrasiveness, but causing the razor to conform to the strop, while the strop at the same time conforms more fully to the cutting edge of the razor. The strop thus constructed produces the required degree of friction and the desired keenness of edge in much quicker time, and consequently with the expenditure of much less labor and with less wear upon the razor. Another advantage of this form of razor-strop is found in the fact that it will not gum up, as the perforations receive the accumulations of grit or other substances from the face of the strop, which is forced therethrough by the action of the razor in the process of stropping the same, the strop thus requiring less frequent cleaning than an ordinary strop without the perforations. The edges of the perforations produce a greatly-increased abrasive surface without increasing the expense of the strop or reducing its strength to an appreciable extent, as the strains upon the strop are comparatively slight. Should the perforations from any cause become partly filled, they can be easily cleaned of the foreign matter by simply dipping the strop in water, as the comparatively small amount of solid material left between the perforations prevents the accumulation of foreign matter except to a very limited extent.

The flexibility of the strop is very materially increased by the presence of the perforations, and this also adds very greatly to its efficiency and operativeness by causing the strop to yield to the movement of the razor and adapt itself thereto. The perforations will preferably be circular, as shown, but may be of other shapes, as preferred, and the perforations may be of any required size and spaced any required distance apart, and I do not, therefore, wish to be limited to any specific size or shape of the perforations or to any specific distance between them.

Having thus described the invention, what is claimed is—

1. As a new article of manufacture a razor-strop composed of a strip of flexible material

and having opposite active faces, the body of the strop being provided with a series of closely-arranged unobstructed perforations extending entirely through the same transversely.

2. As a new article of manufacture a razor-strop composed of a strip of flexible material having opposite active faces of different degrees of abrasiveness, the body of the strop being provided with a series of closely-ar-

ranged unobstructed perforations extending entirely through the same transversely.

In testimony that I claim the foregoing as my own I have hereto affixed my signature in the presence of two witnesses.

WILLIAM H. DOSS.
